[57] ABSTRACT

The audio signal generated by a missile electronic subsection is passed through a threshold detector and into a gate circuit. Output from the memory circuit causes a tone switch to connect a fire tone generator to the gunner's earphone. The fire tone generator produces an audio signal of different frequency and amplitude from that of the "no fire" tone generator.

SYNTHETIC TONE GENERATOR SYSTEM

STATEMENT OF GOVERNMENT INTEREST

The invention described herein may be manufactured and used by or for the government of the United States of America for governmental purposes without the payment of any royalties thereon or therefor.

BACKGROUND OF THE INVENTION

The present invention relates to a synthetic tone generator system and more particularly to a synthetic tone generator system which provides an improved firing tone to a gunner when aiming and firing a missile.

In present day warfare the use of self-propelled missiles and rockets off an ever increasingly important role. Due to their adaptability and long range these missiles are far more effective than any of the previous ballistic projectiles. In adopting a missile to an ever changing environment there frequency occurs the situation wherein the missile is carried aloft in a bomber type aircraft, and then later released to become an air-to-air or an air-to-surface missile. Since these devices are self-propelled there naturally arise problems in having them effectively hit a distant target because once the missile has been launched, then personnel aboard the aircraft which has launched this missile has no further control over it. Naturally, many systems have been devised for the accurate aiming and launching of these missiles, and broadly speaking, most of these systems utilize the radar or other direction seeking means located within the missile itself to aim the missile rather than using any direction finding equipment aboard the aircraft. A signal tone generated by the electronic subsection on the missile is relayed to the aircraft and the bombardier and navigator on the aircraft then maneuvers the plane until the missile is accurately pointed towards the desired target, at which time the missile is released.

While these systems for aiming, arming and releasing a missile from an aircraft are effective, they still nevertheless have a number of drawbacks in that frequently the audible tone from the missile fluctuates and varies in amplitude due to the fact that the target may momentarily move out of range of view, or if the missile itself has a heat seeking device in its nose, then there can be distracting sources of heat other than the target.

The present invention eliminates a number of these shortcomings and weaknesses in prior art systems in that it provides the following advantages:

1. No signal is present during bore sight tracking.
2. There is no unambiguous fire tone present throughout the total field of view when the missile is detecting a target.
3. It eliminates signal level fluctuations due to rapid target aspect angle changes, scintillation, and background hot spots by means of memory feature.
4. Provides for aural indication of hold fire function.
5. Provides a monitoring tone indicating proper circuit operation in the absence of firing tone.

SUMMARY OF THE INVENTION

A tone generator comprising a circuit for comparing a signal generated by a missile subsection with a present level in a threshold detector and when the threshold is exceeded, activating a gate circuit which causes the generating circuit to produce an output so long as the missile audio exceeds the threshold unless inhibited by a hold fire signal indicator signal.

OBJECTS OF THE INVENTION

An object of the present invention is the provision of an improved firing tone for a missile gunner.

Another object of the present invention is the provision of a tone generator system in which no signal null is present during bore sight tracking.

Still another object to the present invention is the provision of a firing tone system which has no unambiguous fire tone throughout the total field of view when the missile is detecting a target.

Yet another object of the present invention is the provision of a firing tone system which eliminates signal level fluctuations due to rapid target aspect angle changes, scintillation, and background hot spots.

5 Yet another object of the present invention is the provision of a firing tone for aural indication of hold fire function.

Still another object of the present invention is the provision of a firing tone system which provides a monitoring tone indicating proper circuit operation in the absence of firing tone.

10 Other objects and many of the attendant advantages of this invention will be readily appreciated as the same becomes better understood by reference to the following detailed description when considered in connection with the accompanying drawings in which like reference numerals designate like parts throughout the figures thereof and wherein:

BRIEF DESCRIPTION OF THE DRAWING

The FIGURE shows a block diagram of a synthetic tone generator system.

DESCRIPTION OF THE PREFERRED EMBODIMENT

Referring now to the lone figure there is shown an input terminal 10 to which is supplied to the audio signal as generated by the missile electronic subsection (not shown). The signal from input terminal 10 is applied to a threshold detector 12 and from thence to a gate circuit 14. Gate, circuit 14 functions to operate a tone switch 16 whose output is applied to an amplifier 18 which in turn is connected to a gunner's earphone 20. Connected so as to apply another input to the tone switch 16 is a no fire tone generator 22, which is one of two indicator tone generators. A fire tone generator 24, which is the other indicator tone generator, supplies to a third input to the tone switch 16.

30 A second input terminal 26 is used to receive a hold fire indicator signal as produced by other fire control equipment (not shown). Connected to input terminal 26 there is a gate inhibit circuit 28, the output of which is used as a second input to inhibit gate circuit 14. A lead 30 which is connected at one end to input terminal 10 is connected at its other end to gate inhibit circuit 28 so as to provide the missile audio tone as a second input to component 28.

35 Turning now to the operation of the invention it can be seen that audio signals generated by the missile electronic subsection are applied to input terminal 10 where it is compared to a preset level in the threshold detector 12. Whenever the target signal-to-noise level exceeds this preset level, a gate circuit 14 is activated. This circuit produces an output as long as the missile audio level is above this threshold level independent of amplitude nulls in the missile audio due to radical design characteristics, and so long as the target is within the angle field of view of the seeker.

40 Output from the gate, circuit 14 causes the tone switch 16 to connect the fire tone generator 24 to an amplifier 18. The output of amplifier 18, whose gain is adjustable, then is connected to the gunner's earphone or audio device 20. The fire tone generator 24 produces an audio signal of different frequency and amplitude than that of the no fire tone generator 22 which is also connected to the tone switch 16.

45 If the gate circuit output from 14 is zero for any reason, such as amplitude is below the threshold, or target is out of the field of view, or the hold fire indicator signal is present on input 26, the tone switch 16 connects the no fire tone generator 22 to the amplifier 18 and gunner's earphone 20. This tone, as noted previously, is of a markedly different (lower) amplitude and frequency than that of the fire tone 24 so that the gunner will have no difficulty in distinguishing between the two indicator tones. It can be seen that if there is a signal on the hold fire input terminal 26 which in turn activates gate inhibit circuit 28, this functions to stop any output from gate circuit 14, deenergizing tone switch 16 and applying no fire tone generator 22 as described above.

50 From the above description of the structure and operation of the invention it is clear that there is presented herein a

synthetic tone generator system which provides many improvements and advantages over prior systems. Here, a reliable audio signal is provided to the pilot and gunner as a firing tone and one which is not subject to signal level fluctuations due to target change for angle, scintillation or background hot spots. Also the elimination of ambiguous fire tone signals throughout the total field of view when the missile is detecting a target is a desirable and sought for end in the field of fire control.

Obviously many modifications and variations of the present invention are possible light of the above teachings. It is therefore to be understood, that within the scope of the appended claims, the invention may be practiced otherwise than as specifically described.

I claim:

1. A synthetic tone generator for use in a missile fire control system comprising:
means for receiving an audio tone from the missile subsection;
second means connected to the receiving means to be activated if the audio tone has reached a preset level;
a gate circuit connected to the second means;
a switch operable by the output of said gate circuit; indicator tone generator connected to an input of said switch;
an amplifier connected to the output of the switch; and
audio means connected to the amplifier for rendering the indicator tone audible to a gunner.
2. The device of claim 1 wherein the second means is a threshold detector.
3. The device of claim 2 wherein the switch is a tone switch.
4. The device of claim 3 wherein the indicator tone genera-

tor includes a nofire tone generator connected to the tone switch.

5. The device of claim 4 wherein the indicator tone generator also includes a fire tone generator connected to the tone switch.

6. The device of claim 5 further including means for receiving hold fire signals;

10 a gate inhibit circuit connected to receive the hold fire signals;

means connecting the audio tone from the missile subsection to said gate inhibit circuit; and

means connecting the output of said gate inhibit circuit to said gate circuit;

15 whereby upon receipt of a hold fire signal said gate inhibit circuit prevents said gate circuit from producing an output in response to a signal from said threshold detector.

7. The device of claim 6 wherein the fire tone generator produces an audio signal of different frequency and amplitude than that of the no-fire tone generator.

8. The device of claim 7 wherein the gate circuit produces an output so long as the missile audio level is above the threshold detector level independent of amplitude nulls in the missile audio due to reticle design characteristics.

9. The device of claim 8 wherein the gate circuit produces an output so long as the target is within the angular field of view of the seeker.

10. The device of claim 9 wherein if the gate circuit output is zero the tone switch connects the no-fire tone generator to the amplifier and gunner's audio means.
